CLOTH NOTCHING DEVICE

Eugene G. Weksel, Brooklyn, N. Y.

Application April 23, 1949, Serial No. 39,269

2 Claims. (Cl. 30—353)

1

This invention relates to a device for notching fabric, or the like.

An object of this invention is to provide a device for notching fabric, or the like, said device having an improved cutter, and being provided with means to prevent the clogging thereof by the portions cut from the body of the fabric in the notching operation. In this connection, it will be understood that in notching fabrics, especially in the garment industry, for marking parts of the garments before they are sewn together, in order to guide the operator in stitching companion parts of the garment together, a multiplicity of parts are disposed one on top of the other in a pile which may be of considerable thickness, for example four to six inches, or more, in thickness. Pursuant to this object of the invention, the cutter is constructed so as to enable such a thick pile of fabric layers to be notched quickly and uniformly, as to the notches in each fabric layer, and without excessive effort.

Another object of this invention is to provide a cloth-notching device of simple construction which may be readily assembled and disassembled and which requires a minimum of maintenance for the proper operation thereof.

The above and other objects, features and advantages of the invention will be fully understood from the following description, considered in connection with the accompanying illustrative drawings.

In the drawings:

Fig. 1 is a front elevation of the improved notching device of the invention;

Fig. 2 is a side elevation of the cutter and its mounting plate;

Fig. 3 is a bottom view of the cutter and mounting plate;

Fig. 4 is a sectional view taken along the line 4—4 of Fig. 2;

Fig. 5 is a bottom view of a portion of the base of the device;

Fig. 6 is a sectional view taken on line 6—6 of Fig. 1;

Fig. 7 is a sectional view taken on the line 7—7 of Fig. 1; and

Fig. 8 is a sectional view taken on line 8—8 of Fig. 6.

Referring to the drawings, the cloth-notching device 10 comprises the preferably rectangular base or cloth plate 12, the vertical tubular standard 14 mounted on said plate, the plunger or actuator 16 mounted for vertical reciprocation in said standard and provided with the cutter 18, the compression spring 20 coiled about said plunger,

and the tubular operating member 22 concentrically disposed about the spring, the plunger, and the standard, and having an operating portion or handle 24 to which the plunger is removably secured, all of said parts being formed of aluminum, or steel, or other suitable material.

The base plate 12 is provided with the beveled end portion 28, adapted to readily slide under a plurality of superposed layers of cloth, or the like, and with a substantially flat upper surface 26 adapted to underlie and support said layers in flat, horizontal position under the cutter. Said upper surface 26 is preferably grooved as indicated at 30 to provide a friction surface 10 adapted to prevent the bottom layers of the material from moving on the upper surface of said base plate during the notching operation. On its under-side, the base plate is provided with the recessed portion or seat 32, adapted to receive 15 the metal retainer or set plate 34 provided with the pointed angular portion 36 extending therefrom and underlying a triangular aperture 38 in the base plate (as illustrated in Fig. 5), in which aperture, a substantially triangular insert or 20 bumper 40, preferably formed of rubber or other resilient non-metallic material, is disposed flush with surface 26, said bumper being thereby retained in said aperture against dislodgement by the cutter 18, on the downward thrust thereof. Set plate 34 is secured, in seat 32, to the under-side of the base plate by screws 42. The base plate is provided, on upper surface 26, with the longitudinally grooved portion or guideway 44 which extends from the end 46 thereof to the 25 shoulder or stop 47 adjacent standard 14 (see Fig. 6). An adjustable stop or gauge 48, provided with the slotted portion 50, is mounted for movement in said guideway longitudinally of the base plate, said gauge being removably secured 30 in a predetermined position therein by set-screw 52 threaded into the bore 54 in base plate 12. If desired, the base plate may have inscribed 35 therein any suitable indicia, such as at 56, to indicate notch sizes, whereby, when end 58 of gauge 48 is positioned in guideway 44 in alignment with one of said indications, a notch of predetermined depth will be cut by the cutter 18, as hereinafter described. The gauge 48 is provided with the recessed portion 60 encompassing 40 the bottom of standard 14 and with the gauge members 62 upstanding therefrom, and between which, the cutter 18 is vertically reciprocated, said members serving to limit the spacing between the fabric and the standard, as determined by 45 the position of gauge 48, to regulate the depth 50 55

of the notch. It will be noted that gauge bars or guides 62 are disposed adjacent cutter element 18 at opposite sides thereof. This enables fabric layers or garment parts having a curved edge, usually a concave edge, to be positioned with such edge under the cutting edges of said cutter element. Also, these positions of the gauge bars close to the sides of the cutter element result in said bars being guard means which afford protection to the user of the device.

The standard 14 is secured to base plate 12 by welding or by other suitable means, and is provided with the longitudinal slot 64, extending from the bottom thereof to a point adjacent the top thereof, the cutter element 18 being reciprocably movable therein. The plunger 16 is provided with the longitudinal slot 66, at the lower end thereof, in which is disposed the cutter plate or shank 68, said plate being secured to the plunger by the counter-sunk screws 70 threaded into bores 72 in the plunger. When the plunger is mounted within the standard, the plate or shank 68 is movable longitudinally of the slot 64 therein whereby the cutter is carried by the plunger between the upright members 62 of the guide 48.

The cutter 18 is preferably formed of hardened steel and comprises the angularly related surfaces or walls 74 and 76 forming a cutting head, said walls having a common front edge 78. As illustrated in Fig. 3, the surfaces 74 and 76 diverge rearwardly from front edge 78 and are spaced equally from the intermediate plate or shank 68, which may be formed integrally therewith, or which may be welded, or otherwise suitably secured thereto. The lower or cutting edges 80 and 82, respectively, of surfaces 74 and 76 are inclined upwardly from the lower pointed cutter end 84, as illustrated in Fig. 4. To secure a more efficient cutting action by providing progressively increasing cutting action of the cutter on the layers of fabric, it is to be noted that the front edge 78 is inclined rearwardly and upwardly from the pointed end 84 (see Fig. 6). The said lower edges are sharpened to readily cut through a plurality of superposed layers of fabric, and due to the angular relation of said edges they cut a V-shaped portion therefrom to provide 40 V-shaped notches therein. The lower edge 86 of plate 68 is preferably also sharpened whereby the V-shaped portions, cut from the fabric, are cut by said lower edge 86 to form two substantially V-shaped portions which readily move upwardly of the cutter, as the cutter cuts downwardly through the layers, in spaces 88, between each of the surfaces 74 and 76 and the plate 68, whereby said cut portions of fabric will not clog the cutter but will travel upwardly and outwardly therefrom. When the device is to be used for notching soft fabric, such as for example dress fabrics or the like, the lower edge 86 of plate 68 need not be sharpened, although it is preferred that said edge be sharpened to act as a cutter as just described. The sharpened edge 86 is, however, desirable especially when the device is to be used for notching hard fabrics. After cutting through the layers of fabric, the point 84 and sharpened edges 80 and 82 will strike resilient bumper 40 which prevents the dulling of said point and cutting edges.

The plunger 16 is provided at its upper end with the threaded portion 90 which threads into the internal bore 92 in knob or handle 24 of the operating member 22 whereby the plunger is reasonably secured therein. It will be understood

that knob 24 need not be fabricated in the illustrated shape but may be of any desired shape and construction, and that the surface of member 22 below knob 24 may be changed or eliminated entirely. The compression spring 20 is coiled about plunger 16 and bears against the operating knob 24 and the upper end of standard 14 whereby, when a downward pressure is applied to the knob, the plunger is moved downwardly thereby carrying the cutter 18 downwardly toward the base plate 12 against the bias of spring 20, the full compression of the spring acting to stop the downward thrust of the cutter, or if desired, an auxiliary stop may be provided on the standard.

The notching device 10 may be readily assembled by removing the set plate 34 from the bottom of base plate 12 and by removing the resilient insert 40 from the aperture 38. Thereafter, the movable plunger 16 having the cutter attached thereto may be inserted into standard 14 through the bottom of base plate 12, with the threaded portion 90 being first inserted and the plunger being moved into the standard so that cutter plate 68 will be engaged in the longitudinal slot 64 therein. Thereafter, the bumper 40 is inserted in the aperture 38 and the set plate 34 is secured in position by screws 42. The spring 20 is positioned over that portion of plunger 16 which projects above standard 14 and the operating member 22 is positioned over the free end of plunger 16, and the threaded portion 90 thereof is threaded into bore 92 of knob 24. The guide 48 is secured in position on base plate 12 by screw 52.

To operate notching device 10, the material to be notched is assembled in superposed layers, all the front edges thereof being flush. Beveled end 28 is slipped under the bottom layer and, since the material is resilient, the layers will all be in flat horizontal disposition on surface 26 with the flush front edges thereof abutting the vertical gauge members 62. To adjust the depth of the notch, the gauge 48 should be pre-set as desired, it being apparent that as the guide members 62 are moved toward edge 46 of the base plate, the depth of the groove will be increased. By forcing knob 24 downwardly, the cutter is thrust rapidly through the layers, the V-shaped cut-portions being again cut by the cutting edge of blade 68 whereby said cut portions are moved upwardly on both sides of the blade through the spaces 88.

From the above description, it will be apparent that in providing a cutting element in which the cutting surfaces diverge rearwardly from a common edge and lie in planes intersecting the vertical axis of the device, in which the cutting edges are inclined upwardly from the bottom point of said edge, in which said common edge is inclined rearwardly to lie in a plane which intersects the vertical axis of the device, and in which an additional cutting edge is provided intermediate the first mentioned cutting edges, there has been provided an improved cutter well adapted to perform the objects herein, when incorporated in the simplified device of this invention.

While I have shown and described the presently preferred embodiment of my invention it will be understood that various changes in the details of construction and in the form and arrangement of parts may be made without departing from the underlying idea or principles.

of this invention within the scope of the appended claims.

Having thus described my invention, what I claim and desire to secure by Letters Patent is:

1. A cutting element for a device for notching the edges of stacked pieces of sheet material comprising a laterally extending shank adapted for the attachment of the cutting element at one side end thereof to an actuating member and having front and bottom edges, angularly related cutting parts joined together in V-defining relation and connected to the front edge of the laterally extending shank, said cutting parts diverging rearwardly from the front edge of the shank and depending below the bottom edge of the shank, said cutting parts having cutting edges on their lower depending ends to cut off portions from the edges of the stacked pieces of the sheet material, said shank having a cutting portion on its bottom edge and within the confines of the cutting edges of the angularly related cutting parts and elevated therefrom whereby to sever the cut-off portions of the sheet material, said angularly related cutting parts respectively defining open passages at the opposite sides of the shank whereby the severed

cut-off portions of the sheet material are directed upwardly and outwardly of said passages as the cutting element is used.

2. A cutting element as defined in claim 1 and said cutting edges on the depending ends of the angularly related cutting parts being upwardly and rearwardly inclined from the joined front edges of the cutting parts.

EUGENE G. WEKSEL.
